[57] CLAIM

The ornamental design for a wall spout, as shown and described.

DESCRIPTION

FIG. 1 is a perspective view of a wall spout embodying my new design;

FIG. 2 is a side elevational view thereof;

FIG. 3 is a top plan view thereof;

FIG. 4 is a perspective view of a modified form of the

wall spout shown in FIG. 1;

FIG. 5 is a side elevational view of FIG. 4; and

FIG. 6 is a front elevational view of FIG. 4.
